US00D557582S

(12) **United States Design Patent** (10) Patent No.: **US D557,582 S**
(45) Date of Patent: **** Dec. 18, 2007**

(54) **CLAMP DEVICE**

(75) Inventors: **Thomas Murray**, Baltimore, MD (US);
Michael Kott, Baltimore, MD (US);
Rodney Milbourne, Abingdon, MD
(US)

(73) Assignee: **Black & Decker Inc.**, Newark, DE
(US)

(**) Term: **14 Years**

(21) Appl. No.: **29/272,271**

(22) Filed: **Feb. 5, 2007**

(51) LOC (8) Cl. **08-05**

(52) U.S. Cl. **D8/73**

(58) Field of Classification Search **D8/74, D8/73, 72, 394, 71; 269/3, 6, 143, 147-149, 269/95, 249, 203; 81/355, 356, 353, 487, 81/10, 326, 327; 29/257; 24/514, 569**

See application file for complete search history.

(57) **CLAIM**

The ornamental design for a clamp device, as shown and described.

DESCRIPTION

This application claims priority to U.S. Patent application Ser. No. 11/611,372, entitled “Clamp Device,” filed Dec. 15, 2006. The disclosure of this patent application is incorporated herein by reference in its entirety.

FIG. 1 is a perspective view of a clamp device according to the present invention;

FIG. 2 is a side perspective view of the clamp device of FIG. 1;

FIG. 3 is a left side view of the clamp device of FIG. 2;

FIG. 4 is a right side view of the clamp device of FIG. 2;

FIG. 5 is a top view of the clamp device of FIG. 2;

FIG. 6 is a bottom view of the clamp device of FIG. 2;

FIG. 7 is a front view of the clamp device of FIG. 2, shown at a larger scale; and,

FIG. 8 is a rear view of the clamp device of FIG. 2, shown at a larger scale.
